(57) **CLAIM**

The ornamental design for a braided boomerang pet toy, as shown and described.

DESCRIPTION

FIG. 1 is a front perspective view of a braided boomerang pet toy embodying my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof;

FIG. 7 is a bottom view thereof; and,

FIG. 8 is a front elevational view similar to FIG. 2, now illustrating a second embodiment of FIG. 1.

1 Claim, 4 Drawing Sheets

FIG. 1

FIG. 2

FIG. 5

FIG. 6

FIG. 7

FIG. 8
